US00D823349S

(12) **United States Design Patent** (10) **Patent No.:** **US D823,349 S**
Hakes et al. (45) **Date of Patent:** **** Jul. 17, 2018**

- (54) **UNDERCARRIAGE TRACK SHOE FOR MOBILE EARTHMOVING MACHINE**
(71) Applicant: **Caterpillar Inc.**, Peoria, IL (US)
(72) Inventors: **David J. Hakes**, Brimfield, IL (US); **Benjamin Jones**, Washington, IL (US); **Gustavo Acosta**, Flossmoor, IL (US); **Benoit Abello**, Dunlap, IL (US); **Jason Beckerdite**, Morton, IL (US)
(73) Assignee: **Caterpillar Inc.**, Deerfield, IL (US)
(***) Term: **15 Years**
(21) Appl. No.: **29/602,889**
(22) Filed: **May 4, 2017**
(51) LOC (11) Cl. **15-03**
(52) U.S. Cl. **USPC D15/28**
(58) **Field of Classification Search**

Primary Examiner — Mark Goodwin(74) *Attorney, Agent, or Firm* — Saidman Design Law Group(57) **CLAIM**

The ornamental design for an undercarriage track shoe for mobile earthmoving machine, as shown and described.

DESCRIPTION

FIG. 1 is a perspective view of an undercarriage track shoe for mobile earthmoving machine showing our new design; FIG. 2 is another perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof. Grayscale shading illustrates contour.
